UNITED STATES PATENT OFFICE.

LEON SCHAEFFER, OF SULPHUR, OKLAHOMA.

DEVICE FOR ADJUSTING THE SPINE.

Application filed November 3, 1925. Serial No. 66,459.

My invention relates to an instrument for adjusting the vertebral column of living vertebrate beings and to appliances for carrying the use of said instrument into effect.

The object of my invention is to produce an instrument or spacer for use in the office or hospital, as well as at bedside or sick room, with more efficiency than adjustments made by the hands or other instruments; to restore spaces between the segments of the vertebra when needed; to adjust the vertebral column of living vertebrate beings so as to relieve impingements of the spinal cord and nerves by the mal-position of the segments of the vertebra and otherwise; greater efficiency through specific application to intervertebral articulations, instead of hit or miss process of pulling of the entire human anatomy as is the case with hand manipulations and other devices known as spinal tractors or traction machines; another object is to properly place the instrument and by its shape and the proper application thereof to raise the articular processes of the vertebra off the impinged nerves, restoring the intervertebral foramen, intervertebral disc spaces and lumen of the neural canal; to release intravertebral connections and restore intervertebral cartilaginous spaces; a machine having centrifugal momentum directly through the perpendicular axis and points of contact effecting bi-segmental movements; a machine utilizing centrifugal force for adjusting and anchoring points of contact to laminae, spinous and transverse processes; a machine to move vertebral segments from any lateral mal-position towards the median line; a machine having automatic levation of the whole axis with its upper and lower appendages by means of coil springs; a machine having automatic levation for the contact instrument and automatic tilting levation; a machine susceptible of gravity and momentum being furnished and supplied through operator's own skillful energy applied to handles and the ability to manipulate same axially; a machine susceptible of combination of anchorage of lamina and spinous processes thus effecting bi-segmental movements; a machine susceptible of a combination of anchorage of laminae spinous processes and transverse processes effecting bi-segmental movements;

Other objects and advantages will more fully appear in the ensuing description and accompanying one-page drawing; of which,

Figure 1 is a perspective view of the device and operating table thereunder.

Figure 2 is an elevational view of the detachable portion of the instrument.

Figure 3 is a side elevation of the same.

Figure 4 is an elevational view of the instrument on the line A—A of Figure 2.

Figure 5 is a sectional view of three segments of vertebrae showing the position of the detachable instrument thereabove.

Like characters of reference designate like parts in all the figures.

1 designates the extremity of the tapered portion of the adjusting instrument, 2 the short outside surface between the extremity and the long surface side 3; 4 designates the opposite or shorter side surface and 5 the surface of the adjusting instrument between the shorter side surface and the extremity 1; 6 designates the outer covering of the adjusting instrument preferably being of soft finish leather, 7 the adhesive tape wrapping around 8 tough pliable rubber, 9 is the elongated handle around which the outer parts of the instrument are built and 10 the cross pin or cross section holding firmly the lower section of the adjusting instrument to the handle member; 11 designates the cross section bracing member integral with the handle 9 and intermediate the lower portion of the adjusting instrument and its T-shaped handle member 14; 12 designates the lateral arms of said middle section ending in torsion angles 13 closely fitting, (when attached to the machine to operate the adjusting instrument) on lateral arms 18 integral with upright portion 17 and curved portion thereof 19, said lateral arms 18 passing through ring shaped aperture 15 at lower end of bifurcations 21 and 22 of axial rod 23; 20 designates a short coil spring connecting handle 14 to arm 22 of axial rod; 25 designates the cross section rod integral with axial rod 23 joining the axial rod in a T-shaped form 24; 26, 27 and 28 designate the weight holding frame sides and ends, said weight holding frame and said cross rod 25 holding a plurality of weights 31 in adjustable position on said weight holding frame and said cross rod 25 as shown by partial perforations 30; 32 designates a cylindrical casing surrounding the axial rod 23 which with bracing members 43 support integral with said casing jointed at 37 carriage rods 33, 34, 35, 36, 38, 39, 40, 41 and 42; the curved central portion 38 of rod 36

fit axially into bore of wheel member 40 traveling on carrier rail 57 having upwardly raised stop ends respectively 73 and 74, said carrier rail connecting integrally with rods 5 72 and 70 and bracing rod 71, the whole securely braced and held in place by heavy platform members 69 and 68; 61—62—63 on rod 34 and 44 on rod 42 designate clamping members securely fastened on said rods; 45 10 designates a rod fastened to said clamping member bent at right angles therewith and another angle with a hook 46 on the end thereof supporting coil spring 47 or a plurality thereof connecting with open wheel 15 member 48 on rod 49 through perforation 51 in flat lug member 50; 52 and 54 designate respectively pulley wheel members on rod 49 with ropes 53 and 55 working thereon; 56 designates ratchet wheel on rod 49 20 having a stud 58 on which is attached coil spring 59 connecting with perforation 15 at end of bifurcation of axial rod; 60 designates extended lug connecting clamping means with rod 49; 64 designates a laterally 25 extending rod connecting with clamping means and with perforated ends thereof 65 from which depends pawl 66 connectedly fitting teeth 67 on ratchet wheel 56; 75 designates the adjusting table; 76 designates a 30 portion of the body of a segment of the vertebra, 80 the superior articular process, thereof, 77 the inferior articular process, 78 foramen, 79 the spinous process, 81 the dorsal portion of the spinous process, and 82 the 35 ventral portion of the spinous process.

It will be apparent that with the patient lying on his venter on the table 75 the adjusting instrument, which I refer to name the "Intra foramen spacer" and which is 40 best shown by Figures 2 and 4, may be used independently of the mechanism thereabove, when so desired; also that vertebra segments may easily be acted on by applying the long lip 5 to 81 the dorsal portion of the spinous 45 process of one segment and the short lip 2 to 82 the ventral portion of the spinous process of the next adjoining segment, and by a forward backward, lateral or axial pressure on the "spacer" when so placed, causes 50 the segments to be spaced therebetween and the lateral nerve branches and possibly the spinal cord itself to be relieved of impingement, or of congestion caused therefrom; also that by a slight backward tilting of the 55 spacer the upper segment would thereby be lifted and the lower segment lowered to a greater extent than by the straight forward pressure; also that by a slight forward tilting of the spacer the upper segment involved 60 would be lowered and the lower segment be raised and pushed downward with relation to the head of the patient to a greater extent than by the straight forward pressure of the spacer; also that by a slight 65 rotating, or torsion movement of the spacer

the segments will be brought into close alignment with the vertebral spinal column, and in all of said adjustments the intervertebral foramen is thus re-established restoring the nerve-branches to freedom for the transmission of nerve stimuli. With this the architectural position of the ribs is re-established and restores the thoracic cavity to freedom and expansion and contraction, and the sacroiliac articulations permit of renewed freedom to the pelvic region. The weight of the mechanism, and the weights thereon serve to act as pressure upon the adjusting instrument to the extent same is needed; and this may be supplemented with additional weight as desired by pressure on the handles 16.

It is also apparent that by placing adjusting instrument, or spacer, in connection with the mechanism as shown in Figure 1 the carriage may be manually moved on the carrier rail 57 from the up-turned terminus 73 to the other up-turned end 74 of the carrier rail, or to any point therebetween, bringing it directly over the patient's body so that a point of contact may be established by the spacer at any portion of the vertebral column from cranium to hips. The lowering and raising of the axial rod 23 through its tubular casing 32 is aided by a plurality of springs 47, and 59, and wheels 52, 54, ropes 53, 55 and ratchet wheel 56, teeth 67 and pawl 66.

When the spacer is desired to be used in connection with the mechanism the torsion fangs 13 are securely placed around cross-bar 18 at the points where they are bent upwardly forming the perpendicular portion 17, the handle 9 fitting into the curved central portion 19 at the horizontal portion at top of perpendicular portion 17 and being securely held in place by a thumbscrew at back of handle 9 (not shown). By adjusting the weights 31 towards the ends of rods 25, 29 and 36 more power may be added to the rotating torsion movements of the spacer when such is desired, or when necessity demands it.

All movements of the instrument as described as applicable to the instrument herein, are obtainable also when the instrument is used in connection with the mechanism.

It will be understood any modifications within the scope of the claimed invention may be made in the construction and operation of the instrument and the mechanism without departing from the principle of the invention, or sacrificing any of its advantages.

Having thus described the invention, what is claimed, and desired to be secured by Letters Patent, is:

1. In combination with an instrument, as described, of a substantial supporting platform and bracing arms thereover, supporting a carriage rail, an operable carriage

thereon, a plurality of weights and weight-supporting members adjustably working in connection with said carriage, a two-way handle member with intermediate bent connecting rods, said instrument, as described, adjustably securely connecting said intermediate rods, an axial rod connecting said weight members by bifurcated arms with said two-way handle member, means for adjustably lowering and raising said weights, weight members, axial rod, bifurcated arms, handle member, and said instrument as described; and means for adjustably removing the whole from a position over the patient's body to its normal position.

2. An instrument of the character described, comprising a handle member having an integral cross-section near its lower end securely holding in place a tough resilient body therearound, a tenacious wrapping of adhesive tape, or other suitable material, therearound, the whole being of an approximately flat rectangular form, its lower end

being tapered with its apex near one flat surface side, causing one long and one short beveled plane surface on said apex end, a casting therearound of soft finish leather, and in combination therewith, of a substantial supporting platform and bracing arms thereover, supporting a carriage rail, an operable carriage thereon, a plurality of weights and weight-supporting members adjustably working in connection with said carriage, a two-way handle member with intermediate bent connecting rods, said instrument, as described, adjustably securely connecting said intermediate rods, an axial rod connecting said weight members by bifurcated arms with said two-way handle member; means for adjustably lowering and raising said weights, weight members, axial rod, bifurcated arms, handle member, and said instrument as described; and means for adjustably removing the whole from a position over the patient's body to its normal position.

LEON SCHAEFFER.
